CLAIM

The ornamental design for a medical injector pen, as shown and described.

DESCRIPTION

FIG. 1 is a perspective view of the medical injector with the cap removed showing our new design;
 FIG. 2 is a front elevation view thereof;
 FIG. 3 is a left side elevation view thereof;
 FIG. 4 is a right side elevation view thereof;
 FIG. 5 is a rear elevation view thereof;
 FIG. 6 is a top plan view thereof; and,
 FIG. 7 is a bottom plan view thereof.

(Continued)

The dashed lines in the figures illustrate the portions of the design that form no part of the claimed design.

1 Claim, 6 Drawing Sheets
